1 Claim

ABSTRACT OF THE DISCLOSURE

The new compounds of the formula

where:

R_1 is hydrogen, alkyl of a maximum of 12 carbon atoms, haloalkyl of a maximum of 12 carbon atoms and a maximum of 3 halogens, cycloalkyl of 3 through 8 carbon atoms, aryl of a maximum of 10 carbon atoms, and phenyl

substituted by a maximum of five of the group consisting of halogen, alkyl of a maximum of 6 carbon atoms, haloalkyl of a maximum of 6 carbon atoms and a maximum of 3 halogens, alkoxy of a maximum of 6 carbon atoms, phenoxy, NO_2 , and

where R_5 is an alkyl of a maximum of 6 carbon atoms;

Z is oxygen or sulfur;

R_2 and R_3 are each independently selected from alkyl of a maximum of 12 carbon atoms, haloalkyl of a maximum of 12 carbon atoms with a maximum of 3 halogens, alkenyl of a maximum of 12 carbon atoms, cycloalkyl of 3 through 8 carbon atoms, alkylene linked through a hetero oxygen atom (i.e. to form a morpholino moiety), aryl of a maximum of 10 carbon atoms, alkaryl of a maximum of 18 carbon atoms, arylalkyl of a maximum of 18 carbon atoms;

R_4 is aryl of a maximum of 10 carbon atoms, and phenyl substituted by a maximum of five of the group consisting of halogen, alkyl of a maximum of 6 carbon atoms, haloalkyl of a maximum of 6 carbon atoms and a maximum of 3 halogens, alkoxy of a maximum of 6 carbon atoms, phenoxy, NO_2 , and

where R_5 is an alkyl of a maximum of 6 carbon atoms; Y is oxygen or an $-NH-$ group;

n is an integer of 0 or 1 with the provisions that when R_1 is hydrogen or haloalkyl then n is 0.

These compounds are useful as herbicides and as insecticides.

This invention relates to new compounds, the method of their preparation and to the method of controlling the

2

growth of plants and insects therewith. The new compounds of this invention are of the formula

where:

10 R_1 is hydrogen, alkyl of a maximum of 12 carbon atoms, haloalkyl of a maximum of 12 carbon atoms and a maximum of 3 halogens, cycloalkyl of 3 through 8 carbon atoms, aryl of a maximum of 10 carbon atoms, and phenyl
15 substituted by a maximum of five of the group consisting of halogen, alkyl of a maximum of 6 carbon atoms, haloalkyl of a maximum of 6 carbon atoms and a maximum of 3 halogens, alkoxy of a maximum of 6 carbon atoms, phenoxy, NO_2 , and

where R_5 is an alkyl of a maximum of 6 carbon atoms;

Z is oxygen or sulfur;

30 R_2 and R_3 are each independently selected from alkyl of a maximum of 12 carbon atoms, haloalkyl of a maximum of 12 carbon atoms with a maximum of 3 halogens, alkenyl of a maximum of 12 carbon atoms, cycloalkyl of 3 through 8 carbon atoms, alkylene linked through a hetero oxygen atom (i.e. to form a morpholino moiety), aryl of a maximum of 10 carbon atoms, alkaryl of a maximum of 18 carbon atoms, arylalkyl of a maximum of 18 carbon atoms;

35 R_4 is an aryl of a maximum of 10 carbon atoms, and phenyl substituted by a maximum of five of the group consisting of halogen, alkyl of a maximum of 6 carbon atoms, haloalkyl of a maximum of 6 carbon atoms and a maximum of 3 halogens, alkoxy of a maximum of 6 carbon atoms, phenoxy, NO_2 , and

40 where R_5 is an alkyl of a maximum of 6 carbon atoms; Y is oxygen or an $-NH-$ group;
45 n is an integer of 0 or 1 with the provision that when R_1 is hydrogen or haloalkyl then n is 0.

50 55 Preferred compounds of the foregoing are where Y is $-NH-$. When n is 0 then preferably R_1 is haloalkyl. When n is 1 then preferably Z is oxygen. Most preferred in each of the foregoing cases are where any phenyl moiety present is substituted by a maximum of three of the recited substituents instead of a maximum of five.

55 The halogens included within the scope of this invention are the whole group consisting of chlorine, bromine, iodine and fluorine.

60 Examples of the various other substituents included in this invention are as follows:

The alkyls represented by R_1 , R_2 , and R_3 can be methyl, ethyl, propyl, sec. propyl, tert. butyl, hexyl and dodecyl.

Haloalkyls represented by R_1 , R_2 and R_3 can be chloromethyl, trifluoromethyl, 1-bromopropyl, 1,1-dichlorobutyl, 1,1,2-trichlorohexyl, and 1-iodododecyl.

Alkenyls represented by R_1 , R_2 and R_3 can be 1-propenyl, allyl, isobut enyl, methallyl, 2-hexenyl, 1-octenyl and 2-dodecenyl.

The cycloalkyls represented by R_1 , R_2 and R_3 can be cyclopropyl, cyclohexyl and cyclooctyl.

Aryls of up to 10 carbon atoms represented by R_1 , R_2 , R_3 and R_4 can be phenyl and naphthyl.

Aralkyls represented by R_2 and R_3 can be benzyl, phenethyl and 12-phenyldodecyl.

Alkaryl s represented by R_2 and R_3 can be 2-methylphenyl, 3-ethylphenyl, 6-isopropylphenyl, p-tert.butylphenyl, 4-hexylphenyl, 4-dodecylphenyl, 2,4-dimethylphenyl, 2-methyl-4-hexylphenyl and 2,4,6-trimethylphenyl.

Substituted phenyls represented by R_1 and R_4 can be p-chlorophenyl, 4-bromophenyl, 2,4,6-trichlorophenyl, any of the alkaryl s aforementioned, 2-chloromethylphenyl, 4-iodomethylphenyl, 3-trifluoromethylphenyl, 2,6-di(1-chloroethyl)phenyl, 4-(1,1-dibromobutyl)phenyl, 4-(6,6,6-trichlorohexyl)phenyl, 2-methoxyphenyl, 3-propoxyphenyl, 4-hexoxyphenyl, 2-nitrophenyl, 2,4-dinitrophenyl, 3-(acetamido)phenyl, 4-(butyramido)phenyl, 4-(caproamido)phenyl, 2-chloro-4-methyl-phenyl, 2-methoxy-4-methylphenyl, 2-methoxy-4-bromophenyl, 2,6-dichloro-4-propylphenyl, 2-chloro-4-propionamidophenyl, 2-ethyl-4-acetamidophenyl, 2-chloro-4-acetamido-6-methoxyphenyl, 3-propyl-4-nitrophenyl, and the like.

Illustrative examples of compounds of this invention are:

- (1) m-(isopropylcarboxamido)phenyl dimethylamino-methylenesulfamate
- (2) p-chlorophenyl dimethylaminomethylenesulfamate
- (3) p-butoxyphenyl N-[1-(N'-methyl-N'-dodecylamino)-methylenesulfamate
- (4) m-nitrophenyl dimethylaminomethylenesulfamate
- (5) 2,3,4,5,6-pentachlorophenyl N-[1-(diethylamino)-2-(ethoxy)ethylidene]sulfamate
- (6) p-methoxyphenyl N-[1-(diethylamino)-2-dodecyl-oxy]ethylidene]sulfamate
- (7) p-chloromethylphenyl N-[1-(diethylamino)-1-phenoxy)methylidene]sulfamate
- (8) 3,4-dichlorophenyl N-[1-(diethylamino)-2-(2,4-dichlorophenoxy)ethylidene]sulfamate
- (9) m-(2-methylpropionamido)phenyl N-[1-(diethylamino)-2-(2,4-dichlorophenoxy)ethylidene]sulfamate
- (10) m-propionamidophenyl N-[1-(diethylamino)-2-(2,4-dichlorophenoxy)ethylidene]sulfamate
- (11) 2,4-dichlorophenyl N-[1-(morpholino)-2-(phenoxy)ethylidene]sulfamate
- (12) p-(2-methylpropionamido)phenyl N-[1-(dimethylamino)-2-(p-nitrophenoxy)ethylidene]sulfamate
- (13) p-nitrophenyl N-[1-(diethylamino)-2-(O-nitrophenoxy)ethylidene]sulfamate
- (14) p-chloro-O-tolyl N-[1-(diethylamino)-2-(p-nitrophenoxy)ethylidene]sulfamate
- (15) p-nitro-m-tolyl N-[1-(diethylamino)-2-(p-nitrophenoxy)ethylidene]sulfamate
- (16) p-phenoxyphenyl N-[1-(diethylamino)-2-(phenoxy)ethylidene]sulfamate
- (17) p-chloro-O-tolyl N-[1-(diethylamino)-2-(phenoxy)ethylidene]sulfamate
- (18) p-nitro-O-tolyl N-[1-(diethylamino)-2-(phenoxy)ethylidene]sulfamate
- (19) p-phenoxyphenyl N-[1-(morpholino)-2-(phenoxy)ethylidene]sulfamate
- (20) p-chlorophenyl N-[1-(diallylamino)-2-(phenoxy)ethylidene]sulfamate
- (21) p-nitrophenyl N-[1-(diethylamino)-2-(phenylthio)ethylidene]sulfamate

- (22) 2,4-dichlorophenyl N-[1-(diethylamino)-2-(phenylthio)ethylidene]sulfamate
  - (23) 2,3,4,5,6-pentachlorophenyl N-[1-(diethylamino)-2-(phenylthio)ethylidene]sulfamate
  - (24) n-[α -(2 - tert.butyl - N,6 - dimethylanilino)methylidene]-N'-(2,6-xylyl)sulfamide
  - (25) N-[2chloro-1-(N-isopropylanilino)ethylidene]-N'- α , α , α -trifluoro-m-tolyl-sulfamide
  - (26) 4'-nitro-N-[2-chloro-1-(N-isopropylanilino)-ethylidene]sulfanilide
  - (27) N-[2-chloro - 1 - (diisobutylamino)ethylidene]-2,6-xylylsulfamide
  - (28) N-[2-chloro-1-(N-isopropylanilino)ethylidene]-2,6-xylylsulfamide
  - (29) m-(2-methylpropionamido)phenyl N-[1-diethylamino-2-(2,4,5-trichlorophenoxy)ethylidene]sulfamate
  - (30) m-propionamidophenyl N-[1-(dimethylamino)-2-(2,4,5-trichlorophenoxy)ethylidene]sulfamate
  - (31) p-nitrophenyl N-[1-(dimethylamino)-2-(2,4,5-trichlorophenoxy)ethylidene]sulfamate
  - (32) 4'-chloro-N-[1-butoxy-1-(N - diethylamino)methylidene]sulfanilide
  - (33) 4'-methoxy-N-[1-phenyl-1-(N-diethylamino)-methylidene]sulfanilide
  - (34) N-[2-(2,4,5-trichlorophenyl)-1-(N-diethylamino)ethylidene]sulfanilide
  - (35) N-[2-(4-methylphenyl)-1-(N-ethyl-N-1-chloroethylamino)ethylidene]sulfanilide
  - (36) 4-methylphenyl N-[1-(methyl-2',6'-dimethylphenylamino)-2-(dodecylthio)ethylidene]sulfamate
  - (37) 4 - chlorophenyl N-[1-(diethylamino)-2-(4-chlorophenylthio)ethylidene]sulfamate
  - (38) N-[1-(N-ethyl-N-2-methylphenylamino)-2-(propylthio)ethylidene]sulfanilide
  - (39) N - [1 - (N - ethyl - N - phenylamino)-2-(4-chloromethylphenylthio)ethylidene]-4-chlorosulfanilide
  - (40) N-[1-(N,N-diethylamino)-2-(phenylthio)ethylidene]-4-nitrosulfanilide
  - (41) N-[1-(N,N-diethylamino)-2-(2-chlorophenylthio)ethylidene]-2-methylsulfanilide
  - (42) N-[1-(N,N-didodecen-2-ylamino)-2-(4-chlorophenylthio)ethylidene]sulfanilide
  - (43) 2,3,4,5,6-pentachlorophenyl N-[1-(morpholino)-2-(phenoxy)ethylidene]sulfamate
- 5 The compounds can all be prepared by the same general procedure. The general procedure involves reacting in a first step, the necessary amide with the chlorosulfonyl isocyanate to form a sulfonyl acetamide. This is followed by the reaction of the sulfonyl acetamide in a second step with the necessary aniline or phenol. Illustrative detailed examples of this invention will now be set forth.

EXAMPLE 1

55 In a three-neck flask (500 ml.) fitted with a mechanical stirrer, dropping funnel and a drying tube were placed 4 g. or 0.025 mol of N,N-diethyl- α -ethoxy acetamide and 50 milliliters of anhydrous methylene chloride. The solution was cooled in a Dry Ice-isopropanol bath and 3.52 g. or 0.025 mol of chlorosulfonyl isocyanate was added in one portion. The reaction was allowed to stir overnight at room temperature. (At that time an I.R. spectrum showed the disappearance of the isocyanate (NCO) band at 4.5 μ .) Then the theoretical amount (i.e., 6.75 g.) of 2,3,4,5,6-pentachlorophenol accompanied by a theoretical amount of (i.e., 2.5 g.) triethylamine was added dropwise to the solution, which was cooled in an ice-salt bath and the reaction mixture was allowed to stir overnight. The resulting solution was washed with water, the organic phase dried over magnesium sulfate and the solvent was stripped off on a rotary evaporator. Recrystallization of the resulting material from ethanol yielded a white solid having a melting point of 121.5-122.5° C.

Elemental analysis and other data follows:

MW=486.66. Calcd. (percent): C, 34.55; H, 3.52; Cl, 36.43; N, 5.76; O, 13.15; S, 6.59. Found (percent): C, 34.80; H, 3.44; Cl, ____; N, 5.99; O, ____; S, ____.

Both nuclear magnetic resonance (NMR) and infrared spectral analysis confirmed the expected structure 2,3,4,5,6-pentachlorophenyl N-[1-(diethylamino)-2-(ethoxy)ethylidene]sulfamate.

EXAMPLE 2

In a three neck flask (500 ml.) fitted with a mechanical stirrer, dropping funnel and a drying tube were placed 10 g. or 0.045 mol of N,N-diethyl- α -phenylthioacetamide and 100 milliliters of anhydrous methylene chloride. The solution was cooled in a Dry Ice-isopropanol bath and 6.5 g. or 0.045 mol of chlorosulfonyl isocyanate was added dropwise. The reaction was stirred about 20 hours at room temperature, then 6.9 g. or 0.05 mol of p-nitrophenol dissolved in acetone and methylene chloride and 10.1 g. of triethylamine were added to the solution. The flask and contents was cooled in an ice-salt bath and the reaction mixture was allowed to stir several hours. The resulting solution was washed with water, the organic phase dried over magnesium sulfate and the solvent was stripped off. Recrystallization of the resulting material from ethanol yielded a yellow solid having a melting point of 86.9-88.1° C.

Nuclear magnetic resonance analysis confirmed the expected structure p-nitrophenyl N-[1-(diethylamino)-2-(phenylthio)ethylidene]sulfamate.

EXAMPLE 3

In a three-neck flask (500 ml.) fitted with a mechanical stirrer, dropping funnel and a drying tube were placed 10 g. or 0.05 mol of N-methyl-N-(2-methyl-6-tert.-butyl-phenyl)formamide in anhydrous methylene chloride. The solution was cooled in a Dry Ice-isopropanol bath and 6.35 g. or 0.045 mol of chlorosulfonyl isocyanate was added. The reaction was allowed to stir until the NMR showed no isocyanate present. Then 12.2 g. or about 0.1 mol of 2,6-dimethylaniline and approximately a theoretical amount of triethylamine was added to the solution, which was cooled in an ice-salt bath and the reaction mixture was allowed to stir several hours. The resulting solution was washed with water, the organic phase dried over magnesium sulfate and the solvent was stripped off. Recrystallization of the resulting material from ethanol yielded a white solid having a melting point of 173-174° C.

Both nuclear magnetic resonance and infra-red spectral analysis confirmed the expected structure N-[α -(2-tert.-butyl-N,6-dimethylanolino)methylidene]-N'-(2,6-xylyl)sulfamide.

EXAMPLE 4

In a three-neck flask (500 ml.) fitted with a mechanical stirrer, dropping funnel and a drying tube were placed 40 g. or 0.55 mol of dimethylformamide dissolved in ether. The solution was cooled to 0° C. and 70.7 g. or 0.5 mol of chlorosulfonyl isocyanate was added and the reaction was allowed to stir about 3 to 4 hours. First, 50.5 g. of triethylamine was added, then 90 g. of 3-(isopropylcarboxamido)phenol was added and the reaction mixture was allowed to stir for one-half to one hour. The resulting solution was washed with water, the organic phase dried over magnesium sulfate and the solvent was stripped off. Recrystallization of the resulting material from ethanol yielded a white solid having a melting point of 126-127° C.

Both nuclear magnetic resonance (NMR) and infra-red spectral analysis confirmed the expected structure m-(iso-

propylcarboxamido)phenyl dimethylaminomethylidene-sulfamate.

The utility of the compounds of this invention, that is, the related herbicidal and insecticidal methods, will now be discussed.

The term "herbicide" as used herein and in the appended claims means materials which (1) effectively control all plants in a given locus or (2) selectively control the growth of one or more plant species in the presence of other plants. In like manner, "herbicidal" is used to identify the overall and selective control activity of the compositions of this invention.

The term "plant" as used herein and in the appended claims is inclusive of dormant seeds, germinant seeds, germinative seeds, emerging seedlings and established woody and herbaceous vegetation including the roots and above-ground portions.

The term "control" as used herein and in the appended claims is inclusive of the actions of (1) killing, (2) inhibiting growth, reproduction or proliferation, and (3) removing, destroying or otherwise diminishing the occurrence and activity of plants and is applicable to any of the stated actions, or any combination thereof.

The terms "insect" and "insecticide" are used herein in their broad common usage to include spiders, mites, ticks, and like pests which are not in the strict biological sense classed as insects. Thus, the usage herein conforms to the definitions provided by Congress in Public Law 104, the "Federal Insecticide, Fungicide, and Rodenticide Act" of 1947, section 2, subsection h, wherein the term "insect" is used to refer not only to those small invertebrate animals belonging mostly to the class Insecta, comprising six-legged, usually winged forms, as beetles, bugs, bees, flies, and so forth, but also to other allied classes of anthropods whose members are wingless and usually have more than six legs, as spiders, mites, ticks, centipedes, and wood lice.

The term "herbicidal or insecticidal composition" as used herein means a novel compound of this invention in combination with an adjuvant to be defined hereinbelow.

EXAMPLE 5

The pre-emergent herbicidal activity of the active ingredients of this invention is demonstrated as follows: A good grade of top soil is placed in aluminum pans and compacted to a depth of $\frac{3}{8}$ " to $\frac{1}{2}$ " from the top of each pan. A predetermined number of seeds of the test plant species are placed on top of the soil in the pans. The seeds are covered with a $\frac{3}{8}$ " layer of soil and the pan leveled. The active ingredient is applied by spraying the surface of the top layer of soil with a herbicidal formulation containing a sufficient amount of active ingredient to obtain the desired rate of active ingredient per acre. For soil incorporation, the chemical is sprayed on and mixed into the soil used to cover the seeds.

The seed-containing pans are placed on a wet sand bench and maintained under ordinary conditions of sunlight and watering. The plants are observed at the end of approximately 14 days and the results recorded. The herbicidal activity index is based on the average percent control of each seed lot. The herbicidal activity index is converted to a relative numerical scale for the sake of brevity and simplicity in the table.

The pre-emergent herbicidal activity index used is defined as follows:

Average percent control:	Numerical scale
0 to 25	0
26 to 50	1
51 to 75	2
76 to 100	3

In Table I below, the dosage rate, method of application, the spectrum of plant seeds treated, and the results of tests using compounds of this invention carried out according to the above procedure are indicated.

TABLE I

Cpd.	Dosage, lbs./acre	Kochia	Morning glory	Wild oat	Brome	Rye grass	Radish	Sugar beet	Cotton	Corn	Foxtail	Barn-yard grass	Crab grass	Pig-weed
A	10		0									0		
B	10		1	0	0	0	0	0			3	0	2	3
C	10		2									0		
D	10		1									0		
E	1*	0		0	0			0	0	0	0	1	2	1
F	10		0	0	0	0	0	0			3	2	0	2
G	10		3	0	0	0	0	0			0	0	0	0
H	10		0	0	0	0	0	0			0	0	0	0

Cpd.	Soy-bean	Wild Buck-wheat	To-mato	Sor-ghum	Rice	Smart-weed	Cockle-bur	Lambs-quarter	Can-a-dian thistle	Coffee weed	Nut-sedge	Vel-vet leaf	Quack-grass	Johnson grass	Bromus tectorum
A	0	0	0	1		0	0	0	3			0	0	0	0
B															
C						1	1	1	3		0	0	0	2	0
D						0	3	1	0		0				
E	0		2	0	0	0	2	0	3		0				
F	0	0	0	0											
G	0	0	0	0											
H	0	3	0	0											

NOTE.—Soil incorporated all others surface application: A=p-nitrophenyl N-[1-(diethylamino)-2-(p-nitrophenoxy)ethylidene]sulfamate; B=N-[2-chloro-1-(N-isopropylanilino)ethylidene]-2,6-xylylsulfamide; C=p-nitro-m-tolyl N-[1-(diethylamino)-2-(p-nitrophenoxy)ethylidene]sulfamate; D=p-phenoxyphenyl N-[1-(diethylamino)-2-(phenoxy)-ethylidene]sulfamate; E=N-[1-(diethylamino)-2-(2,4-dichlorophenoxy)-ethylidene]-2,6-xylylsulfamide; F=N-[2-chloro-1-(N-isopropylanilino)ethylidene]-a,a,a-trifluoro-m-tolyl-sulfamide; G=m-propionamidophenyl N-[1-(diethylamino)-2-(2,4-dichlorophenoxy)ethylidene]sulfamate; H=2,4-dichlorophenyl N-[1-(diethylamino)-2-(2,4-dichlorophenoxy)ethylidene]sulfamate.

EXAMPLE 6

In a post-emergent herbicidal test, the active ingredients in each case is applied in spray form to 21 day old specimens of the plants (species indicated hereinafter). The herbicidal sprays are acetone-water solutions containing surface active agents and varying amounts of the active ingredient. The solutions are applied to the plants in different pans at rates equal to the desired rate of active ingredient on a per acre basis. The treated plants are placed in a greenhouse and the effects are observed and recorded after approximately 14 days.

The post-emergent herbicidal activity index used in this example is defined as follows:

Numerical scale:

Herbicidal activity

0	No phytotoxicity.
1	Slight phytotoxicity.
2	Moderate phytotoxicity.
3	Severe phytotoxicity.
4	Plants dead.

In Table II below, the dosage rate, method of application, the spectrum of plant seeds treated, and the results

Thereafter is added 0.1 ml. of an acetone solution of known concentration in percent by weight of a compound of this invention (for example an 0.1 ml. of an 0.1% by weight acetone solution of the compound provides a concentration of 5.0 p.p.m. thereof, while 0.1 ml. of an 0.02% by weight acetone solution of the said compound provides a concentration of 1.0 p.p.m. thereof). In the trough of the pouch formed by the paper wick thereof, are placed two corn seeds (*Zea mays*, Hybrid U.S. 13) about one inch apart. Thereupon to the trough and between the seeds is added 8 to 12 ready-to-hatch eggs of the southern corn rootworm (*Diabrotica undecimpunctata howardi*) which eggs were washed (with distilled water) free of the soil in which they were incubated at room temperature for 21 days immediately prior to their placement in the trough. The so-charged growth pouch is then placed in an upright position in an incubator maintained at 80° F. and 70% relative humidity for 14 days. Immediately thereafter, the growth pouches are removed and the extent of kill in percent of the particular species of corn rootworm larvae observed. The results were as follows:

TABLE II

Cpd.	Cone. percent	Morn-ing glory	Wild oat	Brome	Rye grass	Rad-ish	Sugar beet	Fox tail	Crab grass	Pig- weed	Soy- bean	Wild buck- wheat	Tomato	Sor- ghum
H	0.5	2	0	0	0	2	1	0	0	1	2	1	1	1
B	0.5	0	0	0	0	0	0	0	4	0	0	0	1	0
E	0.5	0	0	0	0	0	1	1	3	0	0	0	1	0

NOTE.—0.5% concentration equals about 9-10 pounds per acre dosage rate. H=m-(2-methylpropionamido)phenyl N-[1-diethylamino)-2-(2,4,5-trichlorophenoxy)ethylidene]sulfamate; B=N-[2-chloro-1-(N-isopropylanilino)ethylidene]-2,6-xylylsulfamide; E=N-[2-chloro-1-(N-isopropylanilino)ethylidene]-a,a,a-trifluoro-m-tolyl-sulfamide.

of tests using compounds of this invention carried out according to the above procedure are indicated.

To illustrate the insecticidal activity of the compounds of this invention, tests were carried out on several different species of insects.

65

EXAMPLE 7

The activity of these compounds against the southern corn rootworm (*Diabrotica undecimpunctata howardi*) is demonstrated by the following:

To a growth pouch (diSPO Seed-Pak growth pouch, Catalogue No. B1220, of Scientific Products Division of America Hospital Supply Corporation, Evanston, Ill.) in an upright position is added 20 ml. of distilled water. 75

Compound	Dosage rate (concentration, p.p.m.)	Percent kill
K	5	80
L	5	70
M	5	50
N	5	100
O	5	60

NOTE.—where: K=m-(isopropylcarboxamido)phenyl dimethylaminomethanesulfamate; L is 2,4-dichlorophenyl N-[1-(diethylamino)-p-nitrophenoxy)-ethylidene]sulfamate; M is p-nitrophenyl N-[1-(diethylamino)-2-(phenylthio)ethylidene]sulfamate; N is 2,3,4,5,6-pentachlorophenyl N-[1-(morpholino)-2-(phenoxy)-ethylidene]sulfamate; O is p-chloro-O-tolyl N-[1-(diethylamino)-2-(p-nitrophenoxy)-ethylidene]sulfamate.

EXAMPLE 8

The compounds of the present invention are also effective against the western corn rootworm (*Diabrotica virgifera*). To illustrate this activity an aqueous acetone solution of p-nitrophenyl - N - [1 - (diethylamino) - 2 - (phenylthio)ethylidene]-sulfamate at a concentration of 5 p.p.m. was prepared. About 1 ml. of this solution was used to moisten a sheet of filter paper positioned in a petri dish. Two one-inch sections of corn roots were deposited on the filter paper and the paper was then infested with 5 western corn rootworm larvae. After being maintained for 24 hours at 25° C. and 70% relative humidity, the mortality rate was observed. Under these conditions, 60% of the larvae were killed.

EXAMPLE 9

To illustrate the activity of the compounds of this invention with respect to control of mosquito larvae, tests were carried out employing a standard evaluation procedure on 3-day old early instar yellow fever mosquito 20 larvae (*Aedes aegypti*) and the results were as follows:

Compound	Dosage rate (concentration, p.p.m.)	Percent kill
I-----	2	100
J-----	2	100

NOTE.—I=N-[2-chloro-1-(N-isopropylanilino)ethylidene]-N'- α , α , α -trifluoro-m-tolylsulfamide; J=2,4-dichlorophenyl N-[1-(diethylamino)-2-(phenylthio)ethylidene]sulfamate.

The active ingredients hereindefined are suitable for both pre-emergent and post-emergent plant application. That is, they are effective in controlling the growth of germinant seeds, emerging seedlings, and established vegetation by exposing the seeds, emerging seedlings, the roots, the leaves or other above-ground portions to the action of an effective amount of one or more of these herbicidally active compounds; however, the best results are usually obtained in a pre-emergent application. Such 40 constitutes a preferred embodiment of the method of controlling plants.

In foliar treatment for herbicidal effect, the active ingredients are applied in amounts from about 0.1 to about 50 or more pounds per acre, preferably about 0.1 to 15 pounds per acre in foliar treatments. In soil applications, it is desirable that the active ingredients be distributed to a depth of at least 0.2 inch. In pre-emergence herbicidal applications the active ingredients are usually applied in amounts from about 0.1 to 25 pounds per acre but preferably from about 0.2 to 10 pounds per acre. It is believed that one skilled in the art can readily determine from the teachings of this specification, including, examples, the procedure for any particular desired application.

In insecticidal applications the active ingredient is usually employed at a rate of 0.01 to 50 pounds per acre. Preferably, they are employed in about 0.1 to 25 pounds per acre.

In practicing the insecticidal and herbicidal methods of this invention, the active ingredients can be used alone or in combination with an appropriate material referred to in the art as an adjuvant in liquid or solid form. The 5 usual purpose of adjuvants is to facilitate application of the active composition and at the desired concentration and/or dosage rate. Insecticidal and herbicidal compositions are prepared by admixing the active ingredient with one or more adjuvants which includes diluents, extenders, carriers and conditioning agents to provide compositions in the form of finely-divided particulate solids or dusts, granules, pellets, solutions, dispersions or emulsions. Thus, the active ingredient can be used with an adjuvant such as a finely-divided particulate solid, a liquid of organic origin, 10 water, a wetting agent, dispersing agent, an emulsifying agent or any suitable combination of these.

Suitable adjuvants of the foregoing types are not here defined in detail as to composition, particle size, relative amounts, etc., since they are well known in the art.

In general, the active ingredients may be formulated with the active ingredient in minor or major proportions in accordance with the table below:

25	Type of formulation	Concentration of active ingredient, percent	
		Herbicidal	Insecticidal
30	1. Granules of relatively large particle size.....	5-50	0.1-95
	2. Powdery dusts.....	2-90	0.1-75
	3. Wettable powders.....	2-90	0.1-75
	4. Emulsifiable concentrates.....	5-95	0.1-95
	5. Solutions and suspensions.....	0.01-95	0.0001-95
35	6. One of the less common types of formulations depending on the desired mode of application.....	.01-95	0.001-99

In addition to adjuvants the compounds of this invention can be used in combination with fertilizers and/or other pesticides such as gastropodicides, insecticides, fungicides, nematocides, and/or other phytotoxicants, and the like.

Having now described the invention, many ramifications and modified embodiments will readily occur to those skilled in the art. Insofar as such variations do not depart 45 from the spirit and scope of the invention described in this application, they are intended to be embraced by the appended claim in their broadest construction.

What is claimed is:

50 1. The compound N-(2-chloro-1-(N-isopropylanilino)ethylidene)-N'- α , α , α -trifluoro-m-tolylsulfamide.
